LOOM WITH STATIONARY WEFT SUPPLIES

Charles Clutsom, St. Michaels, Ashby-de-la-Zouch, England

Application June 13, 1941, Serial No. 397,985
In Great Britain June 15, 1940

12 Claims. (Cl. 139—124)

This invention relates to looms with stationary weft supplies, i. e. shuttleless looms, and has reference particularly to such looms of the kind wherein the weft thread is laid in a shed of warp threads by means of a movable member or members with which a thread engaging element or elements, such, for example, as a reciprocatory knitting needle or needles, co-operates or co-operate to interconnect the wefts, as, for example, by forming a knitted selvedge or selvedges, in order to lock the wefts in the woven fabric.

The expression "weft thread" is to be regarded as covering either a single weft thread or a plurality of such threads where the context so admits.

The present invention has for its object to provide, in a loom of the kind concerned, an improved construction and arrangement of the weft laying mechanism applicable more particularly to the production of relatively wide webs, e. g. from 3 or more up to, say, about 12 inches in width, such as pieces of elastic fabric for manufacture subsequently into elastic garments, and pieces of inelastic or so-called rigid fabric for other purposes.

To this end there are provided, in combination, a slidably reciprocatory weft laying member furnished with a thread guiding portion adapted to be deflected in relation to the main portion, and means adapted to effect deflection of the said thread guiding portion from the path of reciprocation of the main portion after passage through the shed on a forward stroke of the weft laying member in such a manner as to present the weft carried thereby to the adjacent thread engaging element.

Preferably, the weft laying member is engaged with guiding means so constructed and arranged that in addition to being moved transversely to the path of the warps, to lay the weft in the shed, the weft laying member, during each forward stroke, is also constrained to approach the co-operating weft engaging element in the warp-wise direction whereby the weft is presented to the weft engaging element in a favourable position for engagement positively by the said element.

In order that the invention may be more clearly understood and readily carried into practical effect, a specific constructional form thereof as applied to a horizontal loom for producing a plain weave with a single weft thread and one knitted selvedge will now be described by way of example with reference to the accompanying diagrammatic drawings, wherein:

Figure 1 is a plan view of so much of said loom as is necessary to illustrate the application of the present improvements thereto,

Figure 1A is a plan view of the loom, the main body of which is shown in Figure 1,

Figure 2 is a front elevational view of a portion of the loom showing the means for operating and guiding the weft laying member,

Figure 3 is a face view of the cam which is employed for controlling the movements of the said member,

Figure 4 is a detail side view of cam means and connections for operating the weft engaging latch needle which works in conjunction with the laying member in the manner hereinafter to be described,

Figure 5 is a part sectional end view taken on the line V—V of Figure 1A,

Figure 6 is a detail plan view of the deflectable thread guiding portion of the weft laying member,

Figure 7 is a front elevational view of the same as seen in the direction of the arrow B in Figure 6,

Figure 8 is a part sectional view taken on the line VIII—VIII of Figure 1A showing a guiding bracket for the weft laying member,

Figure 9 is a plan view of the weft engaging mechanism and shows, more particularly, the manner in which weft thread is presented to the latch needle by the weft laying member, and

Figure 10 is a side view of the same as seen in the direction of the arrow C in Figure 9.

Like parts are designated by similar reference characters throughout the drawings.

Figures 6—10 are drawn to a larger scale than the remaining figures.

In the loom illustrated in Figure 1, the warps *w* normally extend horizontally at the shedding location *S* and a weft engaging knitting needle *1* of the latch type is arranged for lengthwise reciprocation alongside the path of the warps on the opposite side to that from which the weft laying member *2* operates.

The member *2* consists of a long comparatively thin bar provided at its leading end with a yieldable thread guiding portion *3* capable of being deflected in relation to said bar. This thread guiding portion is mainly straight but curved or bent at its operative, i. e. forward, end where it is furnished with porcelain eyes *4* through which the single weft thread *wt* is passed. The bar *2* and the guiding portion *3* are connected together by a strip *5* of spring steel suchwise as to enable the portion *3* to be deflected forwardly against the spring action from the full line position repre-

sented in Figure 6. The manner of deflection of the thread guiding portion is indicated in dot-and-dash lines. As shown more clearly in Figure 7, the spring strip 5 is secured in position to the respective parts by means of rivets 6. Normally the strip 5 serves to hold the straight part of the yieldable thread guiding portion 3 in alignment with the bar 2; this alignment is maintained by reason of contact with the back of the bar of an abutment 3a formed integrally with the thread guiding portion. At its other end the bar 2 is pivotally mounted on a slider block 7 which is in turn mounted between parallel slides 8, 9 fixed on spaced frame members 10 and 11. The said frame members are disposed adjacent and parallel to the path of the warps—on the side from which the weft laying member is to operate. As will be seen from Figure 1, the parallel slides 8, 9 are set somewhat obliquely with respect to the warps *w* and to the selvedge forming knitting needle 1. The pivot for the bar 2 is constituted by a vertical pin 12 the lower end of which is screwed into the top of the slider block 7. The tail end of the bar 2 is rigidly secured to a small bracket 13 carried by a collar 14 which latter is mounted to turn freely upon the pivot pin 12. A split pin 15 inserted through the top of the pivot pin 12 serves to prevent the collar 14 from coming adrift. In this way, therefore, the weft laying member is permitted slight turning movement about the pivot as and for a purpose hereinafter to be explained. Referring to Figure 5 it will be seen that the block 7 is formed with grooved sides for slidable engagement with the opposed inner edges of the slides 8, 9. The bar 2 is arranged to slide through a fixed guiding bracket 16 mounted on the top of the slide 9 at the inner end thereof. This bracket is set at right angles to the obliquely disposed path *p* of reciprocation of the weft laying member and is slotted or gapped at 16a to permit of the passage of the bar 2 through it. As shown in Figure 8 the width of the slot or gap 16a is somewhat in excess of the thickness of the bar 2. A ball bearing 17 mounted in the bracket 16 near the bottom of the slot or gap therein serves to support the bar 2 and thereby facilitate its smooth movement during reciprocation thereof through the shed. A screw 18 capable of being set in an adjusted position by means of a lock-nut 19 extends through one of the side walls of the guiding bracket 16. The purpose of this screw is to vary the effective width of the slot or gap 16a, according to requirements. For instance, any tendency towards excessive lateral movement of the bar 2 within the bracket 16 could be effectively checked by screwing the screw 18 further inwards to an appropriate extent. A plate 20 with an angular extension 20a disposed to bridge the slot or gap 16a above the bar 2 is secured to the front of the bracket 16. The purpose of such a plate is to ensure that the bar 2 shall never, by accident, become displaced upwardly to such an extent as to come entirely adrift from the bracket. It ought to be explained, however, that the provision of means of this character is neither likely to prove essential nor even necessary in some cases.

Near the completion of each forward stroke of the weft laying member, the curved or bent end of the yieldable thread guiding portion 3 comes into contact with a deflector pin 21 whereupon it is deflected in relation to the bar 2 against the spring action to present the weft thread *wt* to the adjacent knitting needle 1 in the manner depicted in Figures 9 and 10. The operative end

21a of the deflector pin is bent downwardly into the path of the thread guiding portion 3 (see Figure 10). As shown in Figure 1, the opposite end of said pin is screw-threaded and adjustably secured within an appropriately tapped small carrier block 22 which is in turn mounted suchwise as to be capable of adjustment angularly upon a supporting bar or bracket 23. In this way provision is made for setting the deflector pin accurately with respect to the weft laying member.

The construction so far described is therefore such that during each forward stroke the weft laying member 2, in addition to being moved transversely to the path of the warps *w* to lay the weft thread *wt* in the shed, is also constrained to approach the deflector pin 21 and hence also the weft engaging knitting needle 1 in the warp-wise direction. By reason, then, of such oblique movement of the weft laying member in conjunction with deflection of the thread guiding portion 3 in the manner aforesaid, the weft thread is presented to the needle 1 in a favourable position for engagement positively by the said needle.

During reciprocation the weft laying member slides back and forth through the guiding bracket 16 substantially along the rectilinear path *p* but is, however, permitted slight turning or swinging movement about the pivot 12 to guard against jamming. It is convenient to mention here that if the weft laying member was definitely held from such movement there might be a tendency, owing to its speed, for it to bind in the bracket 16 and effect breakages.

A thread tensioning device or devices may be provided in conjunction with the weft laying member to keep the weft thread taut. Conveniently, and as shown in Figures 1, 2 and 5, a tensioning device comprising a pair of discs 24 and a spring 25 for holding or pressing the discs together with the thread *wt* between them is mounted together with thread guiding eyes 26 on a support 27. This support is carried at the upper end of a vertical rod 28 which is fixed in the slider block 7 by means of a screw 29.

The slider block 7 is operated by a lever 30 pivoted in the loom on a bracket 31 which is attached to a cross bar 32 forming part of the main frame of the loom (see Figures 2 and 5). The upper end of this lever is provided with a transversely extending pin 33 which is adjustable heightwise as occasion demands within a slot 30a formed in the said lever. The pin 33 is set in the desired position by a nut 34, and has slidably mounted upon it a double eye piece 35 which is also similarly mounted upon a portion of the aforesaid vertical rod 28 extending through and depending beneath the slider block 7. Accordingly, as the lever 30 is oscillated about its pivot to effect reciprocation of the slider block 7 along the obliquely disposed slides 8, 9, the eye piece 35 slides not only up and down the rod 28 but also back and forth along the pin 33. A gimbal joint is employed to connect the lever 30 with the bracket 31. Thus, as will be seen, the lower end of the lever is suitably enlarged and bifurcated at 30b for reception of an element 36 formed with pintles 37 arranged to turn in the lever. The element 36 is also adapted to turn upon a pivot pin 38 secured in the bracket 31. The axis of the pin 38 extends at right angles to the common axis of the pintles 37. When it is oscillated the lever 30 turns about the axis of the pivot pin 38. The lever 30 is connected by means of a pin 39 and an associated anti-friction device 40 with an arcuately slotted extension 41a at one end of a

cross bar 41 which is slidably mounted in bearings 44 on the frame of the loom. The device 40 comprises a pair of spaced links 42 carrying between them rollers 43 mounted in a slotted guideway 30c in the lever 30. The links 42 are arranged to pivot upon the pin 39. The end of the cross bar 41 remote from its slotted extension 41a is fitted with a truck or roller 45 (see more particularly Figure 3) adapted to engage in an appropriately shaped groove 46 formed in one face of a rotary plate cam 47. This cam is mounted upon a shaft 48 adapted to be driven from the main shaft 49 of the loom through bevel gearing 50, 51. The arrangement is such that as the cam 47 rotates in the direction of the arrow indicated in Figure 3, the cross bar 41 reciprocates and thereby oscillates the lever 30 which in turn imparts the required reciprocatory movements to the slider block 1 and hence also the weft laying member 2. A cam having a groove of a shape suitable for producing the movements concerned is shown in Figure 3; the concentric portion 46a of the groove 46 enables the weft laying member to pause between strokes.

It is principally the intention to use the weft laying arrangement just described in combination with a latch needle 1 arranged and adapted to operate as specifically described in the specification of my prior Letters Patent No. 2,130,636 for forming a knitted selvedge. That is to say, the needle 1 is attached to a carrier bar 52 slidably mounted for reciprocation on a bracket 53 between two plates 54 and 55 which latter together constitute a guide for the bar. The said bar is provided with a laterally extending peg 56 whereby it can be reciprocated. The portion of the bracket 53 upon which the carrier bar 52 is mounted is comparatively narrow, the plate 54 being secured by screws 57 to the inner face of this portion, while the plate 55 is similarly secured by screws 58 to the other side of said portion. As will be seen more clearly in Figure 9, the needle 1 is inclined so that its hook 1a lies in a plane which is obliquely disposed with respect to the plane of the plate 54. A cam 59, formed on a part disposed beneath the carrier bar 52 and attached to the top of the bracket 53, is provided so that when the needle 1 is advanced to engage weft thread presented to it by the weft laying member 2 such engagement is facilitated as the result of contact between the carrier bar and the said cam. The underside of the carrier bar is appropriately shaped to co-operate with the cam 59 in such a way that on each forward stroke of the bar the latter is lifted at its forward end, as shown in Figure 10, to effect deflection of the needle. A blade spring 60 arranged as shown is provided to depress the bar 52 and hence return the needle to its normal level when the bar is retracted. The forward edge of the plate 54 constitutes a knocking-over edge; the elongation of loops drawn by the needle and the casting-off of old loops is facilitated by this edge. Referring to Figure 1 it will be seen that the needle 1 is operated from a profile cam 61 through intermediate connections including a connecting rod 62. The cam 61 is mounted on the conventional crank shaft 63 of the loom from which the customary batten 64 is operated. The approximate shape of the said cam is represented in Figure 4. The connecting rod 62 is provided with a forked or slotted big end 65 embracing the crank shaft 63 and fitted with a roller 66 held up to the cam 61 by a tension spring 67. One end of this spring is anchored to a hooked collar 68

adjustable on the connecting rod 62, the other end being attached to any suitable fixed part of the loom. The rear end of the connecting rod is adjustably secured within a boss formed on the big end 65, while at its forward end the said rod is pivotally connected to a lever 69 secured on a rockshaft 70. Another lever 71 fast on this rockshaft is engaged with the aforesaid peg 56. Consequently, as the cam 61 revolves the rockshaft 70 oscillates to effect reciprocation of the needle 1 in proper timed relation with the movements of the weft layer 2. If desired, the connecting rod may be adjustably connected with the lever 69. In any event, the arrangement is preferably such as to enable the stroke of the needle 1 to be varied or to suit needles of different lengths.

For constraining the fabric to follow a definite path in the region of the fell there are provided spaced bars 72 and 73 between which the fabric *f* passes as produced. The bars 72 and 73 are attached at one end to a bracket 74 fixed to the front of the loom. In lieu of the spaced bars a slotted bar or rod may be provided.

In further explanation of Figure 9 it is convenient to mention that the last picks of weft to be laid at the fell of the fabric are shown at *a* and *b*. At the stage represented in this figure, the needle 1 is fully advanced with a loop *c* of weft thread previously formed at the edge of the fabric on the needle stem below the open latch 1b. The weft laying member 2 is at the end of a forward stroke with the thread guiding portion 3 deflected by reason of its contact with the deflector pin 21. The pick *d* of weft thread carried through the shed at this forward stroke is shown extending across the needle 1 which latter by reason of its upward deflection is in engagement with the thread. In Figure 1, the member 2 is shown during a reverse stroke at which time the thread presented to the needle is drawn into the hook 1a thereof. No further description of the selvedge knitting operation is considered necessary; such operations are now broadly well known and, in any event, are clearly described in my prior patent aforesaid.

In association with the knitting needle 1 there is provided a pin 75 which is arranged and operable for action upon the inserted weft at the fell of the fabric in such a manner that the said weft is held back at such times as the needle is moved to engage weft thread presented by the deflected thread engaging portion 3. That is to say, the pin 75 functions to hold back on the needle previously formed loops such as that indicated at *c* in Figures 9 and 10. The pin 75 is arranged for movement substantially at right angles to the inserted weft towards and from the fell of the fabric at one side thereof in close proximity to the outermost warp. The said pin is carried by a lever 76 which is pivoted at one end of a spindle 77 adjustably secured in a small block 78 attached to the top of the bar 73. The lever 76 is spring influenced normally to maintain the pin 75 in its operative position (depicted in Figures 9 and 10) by means of a torsion spring 79. The upper end of the lever 76 is adapted to be acted upon at appropriate times by a part such as 80 (Figure 1) or on the batten. When so acted upon, the lever is swung about its pivot against the spring action to lift the pin 75 to an inoperative position. The pin is therefore rendered inoperative each time the batten, with its reed or sley, moves forward to beat up the weft.

A spiked roller 81 is provided to engage the fab-

ric as produced in such a manner as to ensure that the edge portion of the fabric is held up to the selvedge-forming mechanism.

Crank or eccentric means instead of cam means may, if desired, be provided for operating the weft laying member.

Instead of a latch needle a bearded needle may be used to knit the selvedge.

According to another embodiment of the invention (not shown) a substantially straight weft laying member is pivotally mounted on a carrier arranged for to and fro movement in relation to the path of the warps, and is slidably connected with a pivoted guide, the pivot for the said member and the pivoted guide being so disposed relatively to the carrier that the weft laying member is constrained to deviate from a path normal to the path of the warps so as to approach the weft engaging element, in the manner described, on the forward strokes. Alternatively, the weft laying member may be bent suchwise that when the bent portion comes into contact with the guide, during the forward strokes of the said member, deviation of the weft laying member from a path normal to the path of the warps to bring the said member up to the weft engaging element, as aforesaid, is achieved.

There may be more than one weft laying arrangement for producing one and the same piece of fabric. For example, the arrangement may be duplicated. There may for instance be a pair of weft laying members consisting of rods or bars and associated guides arranged in parallel relation and both associated with the same carrier or slider, or independent carriers or sliders, for producing double-faced fabric, such duplicate arrangement being adapted to present two wefts to the same thread engaging element, or to separate elements respectively.

In a loom adapted to produce a number of pieces of fabric, web or the like simultaneously there will be as many units or mechanisms embodying the improved weft laying arrangement and a weft engaging element or elements as pieces to be woven, in which case the weft laying members and likewise the weft engaging elements may be operated either by independent sets of actuating mechanism or by actuating mechanism common to all.

What I claim then is:

1. In a weaving loom, in combination, a slideable reciprocatory weft laying member adapted to operate to carry weft thread to and fro through a shed of warps, said member having a thread guiding portion capable of deflection in relation to the remainder thereof, a thread engaging element adapted to operate in conjunction with the weft laying member to ensure laying of the weft to and fro through the shed and to interconnect the wefts, means for effecting deflection of the said thread guiding portion from the path of reciprocation of the weft laying member after passage through the shed on a forward stroke, and guiding means with which the weft laying member is associated, the construction and arrangement of said last mentioned means being such that in addition to being moved transversely to the path of the warps to lay the weft in the shed the weft laying member, during each forward stroke, is also constrained to approach the co-operating weft engaging element in the warpwise direction to facilitate deflection of the thread guiding portion and thereby present the weft to the weft engaging element in a favourable position for engagement positively by the said element.

2. In a weaving loom, in combination, a slideable reciprocatory weft laying member adapted to operate to carry weft thread to and fro through a shed of warps, said member having a yieldable thread guiding portion capable of deflection in relation to the remainder thereof, a thread engaging element adapted to operate in conjunction with the weft laying member to ensure laying of the weft to and fro through the shed and to interconnect the wefts, a fixed deflector which is arranged in the path of reciprocation of the weft laying member and adapted to make contact with and deflect the yieldable thread guiding portion after passage of the weft laying member through the shed on a forward stroke, and guiding means with which the weft laying member is associated, the construction and arrangement of said last mentioned means being such that in addition to being moved transversely to the path of the warps to lay the weft in the shed the weft laying member, during each forward stroke, is also constrained to approach the fixed deflector in a warpwise direction suchwise as to guide the thread guiding portion into contact with said deflector to facilitate deflection thereof and thereby present the weft to the weft engaging element in a favourable position for engagement positively by the said element.

3. In a weaving loom, a combination according to claim 2, wherein the deflector is in the form of a pin adjustably mounted on a fixed support.

4. In a weaving loom, in combination, a slideable reciprocatory weft laying member adapted to operate to carry weft thread to and fro through a shed of warps, said member comprising a main portion in the form of a bar and a thread guiding portion which is yieldable by reason of being connected to said bar by means of a spring strip, a thread engaging element adapted to operate in conjunction with the weft laying member to ensure laying of the weft to and fro through the shed and to interconnect the wefts, means for effecting deflection of the said thread guiding portion from the path of reciprocation of the weft laying member after passage through the shed on a forward stroke, and guiding means with which the weft laying member is associated, the construction and arrangement of said last mentioned means being such that in addition to being moved transversely to the path of the warps to lay the weft in the shed the weft laying member, during each forward stroke, is also constrained to approach the co-operating weft engaging element in the warpwise direction to facilitate deflection of the thread guiding portion and thereby present the weft to the weft engaging element in a favourable position for engagement positively by the said element.

5. In a weaving loom, in combination, a weft laying member having a thread guiding portion capable of deflection in relation to the remainder thereof, a movable carrier upon which said member is mounted, guiding means for said carrier arranged obliquely in relation to the path of the warps, means for reciprocating the carrier along the guiding means whereby the weft laying member operates and moves in an oblique manner to carry weft thread to and fro through a shed of the warps, a thread engaging element adapted to operate in conjunction with the weft laying member to ensure laying of the weft to and fro through the shed and to interconnect the wefts, and means for effecting deflection of the afore-

said thread guiding portion from the oblique path of reciprocation of the weft laying member after passage through the shed on a forward stroke suchwise as to present the weft carried thereby to the thread engaging element.

6. In a weaving loom, in combination, a weft laying member having a thread guiding portion capable of deflection in relation to the remainder thereof, a slidable carrier with which the weft laying member is connected, slides on which the carrier is mounted, said slides extending in an oblique direction with respect to the path of the warps at the shedding location on one side thereof, a fixed guide mounted at the end of the slides adjacent to said path and in which the weft laying member is slidably engaged, means for reciprocating the slidable carrier along the slides whereby the weft laying member operates and moves in an oblique manner to carry weft thread to and fro through a shed of the warps, a thread engaging element adapted to operate in conjunction with the weft laying member to ensure laying of the weft to and fro through the shed and to interconnect the wefts, and means for effecting deflection of the aforesaid thread guiding portion from the oblique path of reciprocation of the weft laying member after passage through the shed on a forward stroke suchwise as to present the weft carried thereby to the thread engaging element.

7. In a weaving loom, a combination according to claim 6, wherein the weft laying member is pivotally connected to the carrier to prevent it binding in the fixed guide.

8. In a weaving loom, in combination, a weft laying member having a yieldable thread guiding portion capable of deflection in relation to the remainder thereof, a movable carrier upon which said member is mounted, guides for said carrier arranged obliquely in relation to the path of the warps, means for reciprocating the carrier along the guides whereby the weft laying member operates and moves in an oblique manner to carry the weft thread to and fro through a shed of the warps, a thread engaging element adapted to operate in conjunction with the weft laying member to ensure laying of the weft to and fro through the shed and to interconnect the wefts, and a fixed deflector which is arranged in the oblique path of reciprocation of the weft laying member and adapted to make contact with and deflect the yieldable thread guiding portion after passage of the weft laying member through the shed on a forward stroke suchwise as to present the weft carried by said member to the thread engaging element.

9. In a weaving loom, in combination, a weft laying member having a yieldable thread guiding portion capable of deflection in relation to the remainder thereof, a movable carrier upon which said member is mounted, guides for said carrier arranged obliquely in relation to the path of the warps, a pivoted lever, means for connecting said lever with the carrier, cam means for effecting oscillation of the lever whereby the carrier is reciprocated along the guides so that the weft laying member is moved in an oblique manner to carry the weft thread to and fro through a shed of the warps, a thread engaging element adapted to operate in conjunction with the weft laying member to ensure laying of the weft to and fro through the shed and to interconnect the wefts, and a fixed deflector which is arranged in the oblique path of reciprocation of the weft laying member and adapted to make contact with

and deflect the yieldable thread guiding portion after passage of the weft laying member through the shed on a forward stroke suchwise as to present the weft carried by said member to the thread engaging element.

10. In a weaving loom, in combination, a weft laying member having a thread guiding portion capable of deflection in relation to the remainder thereof, a movable carrier upon which said member is mounted, guides for said carrier arranged obliquely with respect to the path of the warps, a slotted lever pivoted in the loom, means for connecting said lever with the carrier, a slidable reciprocatory bar with a slotted end, an anti-friction device carried by said slotted end and arranged to work in the slot in the pivoted lever, a cam for effecting reciprocation of the bar, whereby through oscillation of the lever the aforesaid carrier is reciprocated along the guides so that the weft laying member is moved in an oblique manner to carry the weft thread to and fro through a shed of the warps, a thread engaging element adapted to operate in conjunction with the weft laying member to ensure laying of the weft to and fro through the shed and to interconnect the wefts, and means for effecting deflection of the said thread guiding portion from the oblique path of reciprocation of the weft laying member after passage through the shed on a forward stroke whereby the weft is presented to the weft engaging element in a favourable position for engagement positively by the said element.

11. In a weaving loom, in combination, a slid- 35 able reciprocatory weft laying member adapted to operate to carry weft thread to and fro through a shed of warps, said member having a thread guiding portion capable of deflection in relation to the remainder thereof, a guide, a knitting needle attached to a carrier bar slidably mounted for reciprocation in said guide, said needle being adapted to operate in conjunction with the weft laying member to ensure laying of the weft to and fro through the shed and to 40 form a knitted selvedge, a cam for effecting deflection of the needle on the forward strokes whereby positive engagement of the weft with the needle is facilitated, a part providing a knocking over edge adjacent to the needle to facilitate 45 formation of the selvedge, a guide for supporting fabric adjacent to the fell while being woven, means for effecting deflection of the said thread guiding portion from the path of reciprocation of the weft laying member after passage through 50 the shed on a forward stroke, and guiding means with which the weft laying member is associated, the construction and arrangement of said last mentioned means being such that in addition to being moved transversely to the path of the warps to lay the weft in the shed the weft laying member, during each forward stroke, is also constrained to approach the co-operating knitting 55 needle in the warpwise direction to facilitate deflection of the thread guiding portion and thereby present the weft to the knitting needle in a favourable position for engagement positively by the said needle.

12. In a weaving loom, in combination, a slid- 70 able reciprocatory weft laying member adapted to operate to carry weft thread to and fro through a shed of warps, said member having a thread guiding portion capable of deflection in relation to the remainder thereof, a thread engaging element adapted to operate in conjunction with the weft laying member to ensure laying

of the weft to and fro through the shed and to interconnect the wefts, means for effecting deflection of the said thread guiding portion from the path of reciprocation of the weft laying member after passage through the shed on a forward stroke, guiding means with which the waft laying member is associated, the construction and arrangement of said last mentioned means being such that in addition to being moved transversely to the path of the warps to lay the weft in the 10 shed the weft laying member, during each for-

ward stroke, is also constrained to approach the co-operating weft engaging element in the warp-wise direction to facilitate deflection of the thread guiding portion and thereby present the weft to the weft engaging element in a favorable position for engagement positively by the said element, and means whereby when the thread engaging element is moved to take the weft the previously formed portion of the selvedge is held back on said element.

CHARLES CLUTSM.
